UNITED STATES PATENT OFFICE.

CAESAR KIEVE, OF BROOKLYN, NEW YORK, ASSIGNOR TO HEATHER HANDKERCHIEF WORKS, OF NEW YORK, N. Y., A CORPORATION OF NEW YORK.

DESIGN FOR A HANDKERCHIEF.

56,816.

Specification for Design.

Patented Dec. 28, 1920.

Application filed May 24, 1919. Serial No. 299,676. Term of patent 3½ years.

To all whom it may concern:

Be it known that I, CAESAR KIEVE, a citizen of the United States, residing at Brooklyn, in the county of Kings and State of New York, have invented a certain new, original, and ornamental Design for Handkerchiefs, of which the following is a specification.

Said design consists in an ornamental design for a handkerchief as illustrated in the accompanying drawing, wherein Figure 1 illustrates a handkerchief as a whole embodying my new design and Fig. 2 is a fragmentary showing of one corner of Fig. 1 on an enlarged scale showing more clearly the ornamental character of the handkerchief as it appears in actual size.

What I claim is:

The ornamental design for a handkerchief herein shown and described.

In witness whereof I have hereunto set my hand at Brooklyn, New York, this 17th day of May, A. D. nineteen hundred and nineteen.

CAESAR KIEVE.

Witnesses:

ABE WORMS,
JOHN WAGUWILLEY.
